CLAIM

The ornamental design of a container for cosmetic serum, as shown and described.

DESCRIPTION

FIG. 1 is a front view of a container for cosmetic serum;
FIG. 2 is a left view thereof;

FIG. 3 is a back view thereof;

FIG. 4 is a right view thereof;

FIG. 5 is a perspective view thereof;

FIG. 6 is a top view thereof; and,

FIG. 7 is a bottom view thereof.

The broken lines and the areas within FIG. 7 depict portions of a container for cosmetic serum that form no part of the claimed design.

1 Claim, 7 Drawing Sheets
